UNITED STATES PATENT OFFICE.

WILLIAM H. HARGRAVES AND JOHN SIDNEY HEILIG, OF ALLENTOWN, AND JACOB ROBERTS, OF CATASAUQUA, PENNSYLVANIA.

TACKING ATTACHMENT FOR SEWING-MACHINES.

SPECIFICATION forming part of Letters Patent No. 678,398, dated July 16, 1901.

Application filed February 16, 1900. Serial No. 5,406. (No model.)

To all whom it may concern:

Be it known that we, WILLIAM H. HARGRAVES and JOHN SIDNEY HEILIG, of Allentown, and JACOB ROBERTS, of Catasauqua, 5 Lehigh county, Pennsylvania, have invented a new and useful Improvement in Tacking Attachments for Sewing-Machines, of which the following is a specification.

Our invention has for its object to provide 10 an attachment for sewing-machines which shall be adapted to tack the corners of pockets, buttonholes, crotches, &c., wherever the parts are subjected to special strain, which would otherwise tend to rip or tear the sewed 15 parts of the garment.

We will describe a device embodying our invention and then point out the novel features thereof in the claims.

Our attachment is illustrated in the accompanying drawings, wherein like letters of reference refer to similar parts in the several views.

Figure 1 is a top or plan view of the attachment. Fig. 2 is a side elevation of the same.

25 Fig. 3 is a vertical longitudinal section on the plane of the line 3 3 of Fig. 1. Fig. 4 is an inverted plan view of the bottom of the attachment. Fig. 5 is an end elevation of a cam-wheel looking from the front of the attachment. Fig. 6 is a plan view of a part of a friction-clutch device forming a part of the attachment, and Fig. 7 is a plan view of the clutch-operating lever.

35 *a*, *a'*, and *a''* designate, respectively, the bed portion, the cam-wheel casing, and the lugs for embracing the presser-foot bar, all of which parts are formed integral with each other and constitute what may be termed the "fixed" body or frame of the device. One 40 of the lugs *a'* is provided with a jam-screw *a''* for clamping or adjustment to the presser-foot bar of the sewing-machine, and thereby securing the same in its proper working position. In the fixed casing *a'* is journaled a 45 shaft *b*, on the projecting end of which is keyed or otherwise secured a ratchet-wheel *b'*. On the said shaft *b*, between the casing *a'* and the ratchet-wheel *b'*, is pivoted a lever *b''*, which is provided with a spring-held 50 pawl *b'''* in engagement with said ratchet-wheel. One end of the spring *b''* bears in a

groove on the top of the pawl *b'''*, and its other end is seated in a groove in the washer *b''* and clamped between said washer and a flat-headed screw *b'''*, having engagement with the 55 lever *b''*. By seating the spring *b''* in a groove in the top of the pawl the said spring is prevented from being knocked or crushed out of place by the work or other means when the attachment is in operation. 60

To impart a rotary movement to the ratchet-wheel *b'*, we connect the forward end of the lever *b''* with the needle-bar of the machine by means of a link having two eyes whose axes are at right angles to each other, the said end 65 of the lever *b''* having sliding connection with the eye *b''* of this link. The other eye *b''* of this link is secured on the needle set-screw or clamp of the needle-bar, so as to impart an oscillating movement to the link. Hence under the reciprocating motion of the needle-bar the lever *b''* will be oscillated, and through the pawl *b'''* and ratchet-wheel *b'* the shaft *b* will receive an intermittent rotary motion in a constant direction. In order to give the desired vibratory movement of the cloth-clamp, we secure on the shaft *b* by a screw *c''* or other suitable means a cam-wheel *c*, having a peripheral zigzag cam-groove *c'*. The cam-groove *c'* of the cam *c* is engaged from below 75 by a roller *c''* on a stud *c''*, formed integral with a lever *c'''*. This lever is fulcrumed on a screw-bolt *c''''*, extending through an opening in the frame portion *a*, the lower end of said bolt being reduced with respect to the body 80 portion and having screw-threaded engagement with the lever *c''''*, against which it is screwed tightly. The projecting screw-threaded portion of the bolt *c''''* is also engaged by a nut *c'''''*, which is screwed up tightly against 85 the lever *c''''* and holds the latter firmly to the bolt *c''''* under the rapid vibratory movement of said lever. The nut *c'''''* also serves to hold the retaining-plate *e* in position. On the lever *c''''* and having dovetailed engagement 90 therewith is a cross-head slide *d*, which may be clamped to said lever *c''''* in any desired position by a set-screw *d'*, which works through a longitudinal slot *e'* in the retaining-plate *e*. 95

Between the cross-head slide *d* and the side 100 walls of the slot *f''* in the cloth-clamp plate are shoes *d''*, which on their inner sides con-

form to the cross-head slide and on their outer sides are grooved to engage the walls of the slot f^7 , so that when placed in position said shoes will be held between the cross-head d^5 and the walls of said slot. These shoes d^2 provide an excellent wearing-surface, and they may easily be replaced when worn out.

In the rear part of the cloth-clamp plate f is a longitudinal slot f^3 , in which works a block f^5 , mounted on a screw f^6 , the body of which screw passes through an opening in the retaining-plate e and also through said block and serves as a fulcrum for the vibratory movement of the cloth-clamp plate and of the retaining-plate e when the parts are in working position. The block f^5 is especially to provide a good bearing-surface at the fulcrum for the longitudinal movement of the plate f . The block f^5 might be dispensed with by having the screw f^6 bear directly against the sides of the slot f^3 ; but such arrangement would not wear well. With the said block there is a good bearing-surface for the oscillation of the block about the screw and for the sliding of the block in the slot f^3 . The reduced threaded part of the screw f^6 is in engagement with an opening in the body of the frame of the attachment. It will thus be seen that the cloth-clamp plate f is held between the bottom of the bed portion of the frame and the retaining-plate e by means of the parts d^1 , c^5 , c^6 , and f^6 . The transverse slot e^2 in the retaining-plate e and the longitudinal slot f^7 in the forward part of the cloth-clamp slide f are of the proper lateral dimensions, so as to afford clearance for the nut c^6 under the lateral swinging or vibrating movement of the cloth-clamp.

By the rotary motion of the cam-wheel c' the lever c^4 will be vibrated in a horizontal plane and will impart a similar motion to the cloth-clamp plate f about its fulcrum f^5 and the retaining-plate e about its fulcrum f^6 . The extent of the throw or amplitude of vibratory movement of the cloth-clamp is determined by the position of the cross-head d on the lever c^4 , the throw being increased as the distance of the said head from the fulcrum of the lever is increased.

The cloth-clamp plate f is provided at its forward end with a serrated cloth-clamp f' , which is rigidly connected to the plate f by screws f^2 engaging holes in the ends of the cloth-clamp plate and passing through slots in lugs projecting from the sides of the cloth-clamp. These slots allow a certain amount of lateral adjustment of the cloth-clamp f' with respect to the plate f . The cloth-clamp is provided with an opening f^4 , which is of such dimensions that the metal portions of said clamp will not at any time be directly under the needle of the sewing-machine.

We will now describe the means by which the cloth-clamp plate is given a progressive longitudinal feed. The rear end of the plate f has a vertical portion f^8 , to which is fastened rigidly by any suitable means the down-

wardly-projecting portion of a cross-head g^{11} , having an opening g , within which travels a block g^3 . This block is secured on the upper face of a disk g^4 by means of a jam-screw g^5 passing through an opening in said block and having screw-threaded engagement with a plate g^6 , which plate has dovetailed engagement with the disk g^4 . The dovetailed groove g^7 , in which the plate g^6 is set, extends diametrically of the disk g^4 , and the thickness of the plate g^6 is a little less than the depth of the groove g^7 , thereby providing a clearance between the top surface of the plate g^6 and the under surface of the block g^3 , so that said plate and block may be adjusted to any desired position radially from the center of the disk g^4 to increase or decrease the extent of travel of the cloth-clamp plate f , according to the length of the tack desired.

Plates or guides g' , fastened rigidly to the cross-head g^{11} by screws g^2 , have downturned portions which extend over the side walls of said opening. These plates provide a simple means of adjustment and for taking up wear.

The disk g^4 is formed with a hub f^9 , which is seated in an opening in the bed portion a of the frame, said hub having a shoulder f^{11} , which bears against the upper surface of said bed portion. On the under surface of the disk g^4 is an annular groove g^8 , into which is placed a clutch-ring formed of halves g^9 , each half having a portion of one end removed, so as to leave a rectangular opening g^{10} between them. Into the opening g^{10} fits a stud h' , rigidly secured to a lever h , fulcrumed on the hub f^9 of the disk g^4 immediately above the bed portion a , the opening h^2 in said lever being such as to provide a clearance between the lever and the hub f^9 . To operate the lever h by the ratchet-wheel b' , we provide a slide-bar i , which rests loosely on a flange a^4 of the frame of the attachment. This slide-bar i has an upturned end i^1 engaging the projecting end h^3 of the lever h , and the other end of the slide-bar i has a pin i^2 , which is engaged by the end of lever b^2 on the upward movement of the outer end of the lever b^2 , received from the reciprocating needle-bar. The inner end of said lever imparts a forward movement to the slide-bar i , thereby giving an intermittent rotary movement to the lever h and giving the stud h' a twisting motion between the ends of the halves g^9 of the clutch-ring and jamming the said halves against the outside of the annular groove g^8 of the disk g^4 . This movement causes the disk g^4 , the ring formed of the halves g^9 , and the lever h to be locked together as one piece rotating on the hub f^9 . When the forward end of the slide-bar i is released by the lever b^2 , the spring h^4 , secured to the lever h and the frame of the attachment, rotates said lever in a direction opposite to that in which it was moved by the slide-bar i . This reverse movement releases the parts of the ring g^9 from engagement with the wall of the groove g^8 and permits the said parts g^9 to slide freely

in said groove. The parts will then be in a position to be rotated again on the next throw of the lever b^2 . The plate g^6 is provided with a stud g^{12} , which fits into an opening in the block g^3 , and as the parts are securely locked together the intermittent rotary motion of the disk g^4 is imparted to the block g^3 , causing the latter to travel longitudinally in the opening g of the cross-head g^{11} . This movement of the block g^3 imparts to the cloth-clamp and plate an intermittent feed lengthwise of the attachment, one complete rotation of the disk g^4 feeding the said plate once forward and backward, a short dwell occurring at the ends of the tack when the block g^3 is at the center of the opening g . The block g^3 may be termed an "equalizing-cam," as it equalizes the successive steps of the progressive longitudinal feed movement of the cloth-clamp plate. In general contour the block g^3 is triangular and its periphery is so curved that the stitches of the tack will be at equal distances from one another except just at the ends of the tack, where several stitches are made to give extra strength and tie the threads.

Any rotation of the clutch-disk g^4 in a direction reverse to that which it receives through the lever h is prevented by a friction spring-washer f^{12} bearing against the under side of the frame a and held in position by a set-screw f^{10} , having screw-threaded engagement with the hub f^9 .

In order to vary the throw of the slide-bar i , it is provided with an upwardly-projecting arm i^3 , which contacts with a stop i^4 , set into the frame a and held from rotation by a set-screw i^5 . This stop is made in the form of a screw having its head eccentric to the body portion, so that by adjusting the same the slide-bar i will be permitted to move a greater or less distance.

What we claim as our invention, and desire to secure by Letters Patent, is—

1. In a sewing-machine attachment the combination with the cloth-clamp plate, of a lever, means to connect said lever with the needle-bar of the machine, a slide-bar actuated by said lever, a clutch device engaged and operated by said slide-bar, said slide-bar

resting loosely on a flange along the side of the frame of the attachment, and means actuated by said clutch device for imparting to the cloth-clamp an intermittent progressive feed movement lengthwise of the attachment, 55 substantially as described.

2. In a sewing-machine attachment, the combination with the cloth-clamp plate, of a shaft carrying a cam, a ratchet-wheel fixed to the cam-shaft, a pawl and pawl-lever for actuating said ratchet-wheel, mechanism intermediate said cam and plate for imparting to the latter a vibratory movement, a slide-bar actuated by said pawl-lever, a clutch device engaged and operated by said slide-bar, 65 said slide-bar resting loosely on a flange along the side of the frame of the attachment, and means actuated by said clutch device for imparting to the cloth-clamp an intermittent progressive feed movement lengthwise of the 70 attachment, substantially as described.

3. In a sewing-machine attachment the combination with the cloth-clamp plate having a slotted cross-head extending transversely to said plate, of means for imparting 75 to said plate a vibratory movement, comprising a lever having means for connecting it to the needle-bar of the machine, a slide-bar resting loosely on a flange along the side of the frame of the attachment actuated by said 80 lever, a clutch device comprising a disk and a lever, the latter being in engagement with said slide-bar, and a block clamped to said disk and engaging the walls of said slot, substantially as described.

In testimony whereof we have signed our names to this specification in the presence of subscribing witnesses.
